FIG. 1 is a front perspective view taken from the top and right side of a lawn sweeper embodying our new design;

FIG. 3 is an enlarged rear perspective view thereof, as shown in FIG. 1; and

FIG. 4 is an enlarged rear perspective view thereof, as shown in FIG. 2.

The dominant features of our design reside in the full line portions of the drawing. It is to be understood however that the showing of a conventional rope fragment in FIGS. 1 and 3 is for purposes of illustration only.

We claim:

The ornamental design for a lawn sweeper as shown and described.
